Steel Lath Company, Niles, Ohio, a corpora-
tion of Ohio

Application March 1, 1940, Serial No. 321,756

5 Claims. (Cl. 164—60)

This invention relates to improvements in machines for slitting expanded metal lath or fabric, such as commonly is used as a base or supporting means for plaster, stucco and the like in building 5 constructions.

Expanded metal lath or fabric of the character with which the present invention is concerned is formed by first providing parallel rows of slits in a flat sheet of metal with the slits in each row spaced apart at their ends and with the spaces 10 between the ends of the slits of each row alined, transversely of the sheet, with the medial portions of the slits of adjacent rows, and by then expanding the sheet transversely. Slitting of a 15 sheet in the manner stated divides the sheet into strands, while transverse expansion of the sheet results in said strands being drawn apart and forming diamond-shaped openings in the sheet. These diamond-shaped openings are, of course, 20 defined by the strands and due to the manner of slitting the sheet, bonds are provided uniting the strands at the corners of the diamond-shaped openings therein. Moreover, when the sheet is expanded the strands and the bonds do 25 not remain in the plane of the sheet, but are caused to twist and assume, in cross section, diagonal relationship to the plane of the sheet. The bonds are, of course, twice as wide as the strands, assuming that the strands are equal in 30 width to each other, as usually is the case, and said bonds are, of course, disposed in rows longitudinally of the sheet.

It is usual to form metal lath of the character stated into sheets of standard lengths and widths 35 and thereafter to cut said sheets into elongated strips of narrow width for special uses.

One common method of cutting sheets of the character stated into narrow strips is to sever the strands of the sheets. This, however, results 40 in the strips having ragged, sharp, barbed edges which cut and tear the hands of workmen handling the strips. Therefore, this manner of cutting the sheets into strips is quite objectionable.

Attempts have been made to provide machines for cutting sheets of the character stated into strips by longitudinally severing the bonds of the sheets midway between their side edges, thereby to avoid ragged, barbed side edges along 45 the strips, but for one reason or another machines heretofore designed for this purpose have not proved entirely successful, one principal reason being that said prior machines have not been constructed to insure positive holding of the 50 sheets in proper relationship to the cutters.

Accordingly, the general object of the present invention is to provide a machine to cut sheets of the character stated into strips by longitudinally severing the bonds of the sheets midway between their side edges, whereby the side edges 5 of the strips will be substantially smooth and devoid of sharp projections, and to so construct a machine for this purpose as to insure that the sheets will be positively held in proper relationship to the cutters to insure cutting of the bonds 10 in the manner stated.

Another object of the invention is to provide a simple machine embodying simple, efficient holding means for the purpose stated and which may be operated at high speed for rapidly cutting 15 sheets into strips without danger of the sheets being cut otherwise than cleanly along lines midway between the side edges of the bonds of the sheets, as is desired.

With the foregoing and other objects in view 20 which will become more fully apparent as the nature of the invention is better understood, the same consists in a machine for the purpose stated embodying the novel features of construction, combination and arrangement of parts as will 25 be hereinafter more fully described, illustrated in the accompanying drawings and defined in the appended claims.

In the accompanying drawings, wherein like characters of reference denote corresponding 30 parts in the different views:

Figure 1 is an end view, partly in section, of a machine constructed in accordance with one practical embodiment of the invention.

Figure 2 is an enlarged detail view of one pair 35 of the cutters and sheet holding means of the machine.

Figure 3 is a detail, longitudinal section through a portion of the machine shown in Fig. 1; and

Figure 4 is a plan view of a section of metal lath of the type which the present machine is 40 designed to cut.

Referring to the drawings in detail, it will be observed that a sheet A of metal lath of the 45 character with which the present invention is concerned has diamond-shaped openings defined by strands 10 which are united with each other at the corners of the openings by bonds 11 disposed in rows longitudinally of the sheet, and 50 that said strands and bonds extend, cross sectionally with respect to the sheet, in stair-step fashion relative to each other.

In order to longitudinally cut a sheet of the character stated into narrower sheets or strips 55

devoid of ragged or barbed side edges it is necessary to longitudinally cut the bonds 11 of the sheet midway between their side edges. Moreover, from a practical standpoint, a machine for doing this must be capable of operating both rapidly and with extreme accuracy.

According to the present invention the cutting means comprises a pair of rotatably driven cutting disks which are laterally and longitudinally offset relative to each other and which are disposed in edge to edge or slightly overlapped, face to face relationship whereby they act as shears, while the sheet holding and guiding means comprises one or more guide disks formed either integrally with or in effect carried by each cutting disk for cooperation with the bonds and the strands of the sheet to either side of the row of bonds to be cut to positively insure proper presentation of each bond to be cut to the cutting disks.

In a machine constructed in accordance with the invention each pair of cutting disks and co-operating holding disks comprises a cutting and holding unit, and there may be only one or as many of these units as desired to cut a sheet into any desired number of strips of any desired widths.

The drawings illustrate by way of example a machine embodying the features of the invention as comprising a frame composed of spaced apart side elements 12, 12 connected together by upper and lower cross members 13 and 14, respectively, and further illustrate by way of example two cutting and holding units mounted upon said frame in laterally spaced apart relationship to simultaneously cut two rows of bonds 11 of a sheet A supported upon a suitable frame-carried table 15 disposed horizontally between the cross members 13 and 14.

Each cutting and holding unit comprises an upper head and a lower head and each head comprises a suitable bracket 16 having suitably journaled therein a shaft 17 which may be rotatably driven in any suitable manner and which carries at one end thereof a cutting disk 18 and cooperating holding disks 19.

The brackets 16 of the upper heads are suitably mounted on the upper cross members 13 and the brackets 16 of the lower heads are suitably mounted on the lower cross members 14, while the cutting and holding disks of the upper heads are carried by the lower ends of the shafts 17 of said upper heads and the cutting and holding disks of the lower heads are carried by the upper ends of the shafts 17 of the latter heads. Moreover, the upper and lower shafts 17, 17 of each unit are disposed in parallel, laterally offset relationship to each other to dispose the cutting disks 18, 18 carried thereby in shear-like relationship to each other, either in edge to edge relationship or in slightly overlapped, face to face relationship as shown. In addition, said shafts 17, 17 are disposed at inclinations to the table 15 corresponding to the inclinations of the strands 10 and the bonds 11 of the sheet A to the plane of said sheet to dispose the cutting disks 18, 18 in planes at right angles to the bonds 11 of a sheet A supported upon the table 15 and to insure proper holding engagement of the guide disks 19 with the strands and bonds of the sheet A to either side of the row of bonds 11 to be cut. In other words, there may be one or more sheet holding and guiding disks 19 either above or below, or both above and below, each cutting disk 18, but preferably there are two or more of

the disks 19 both above and below each cutting disk. In any event, the cutting disks and the holding and guiding disks are axially aligned with each other and are of equal thickness and also are equal in thickness to the width of the strands 10. Moreover, the holding and guiding disks 19 are of different diameters such that their marginal portions are disposed in stepped relationship to each other corresponding to the stepped relationship of the strands 10 of the sheet A to each other. The marginal portions of said holding and guiding disks also have substantially this same stepped relationship to the marginal portions of the cutting disks 18. Furthermore, the cutting disks of each pair are disposed at an elevation such that the points of intersection of their cutting edges or, in other words, their cutting points, are disposed in the median plane of a sheet A supported upon the table 15. In short, each pair of cutting disks 18, 18 are disposed so that when a sheet A is supported flatly upon the table 15 with a row of the bonds 11 aligned with the points of intersection of said cutting disks and if the sheet then is advanced toward the cutting disks, the latter will cut the bonds 11 midway between their side edges, while the holding and guiding disks 19 are disposed to fit into the stepped-like formations defined by the strands 10 and the bonds 11 at both the top and the bottom of the sheet and to either side of the row of bonds 11 to be cut, thereby positively to hold the sheet in proper relationship to the cutting disks to insure that the bonds will be cut midway between their side edges.

Any given cutting disk 18 and its related sheet holding and guiding disks may be formed as a one-piece, stepped element. Preferably, however, the disks 18 and 19 of each head are separate and distinct from one another and are supported in superimposed relationship upon a base disk 20 carried by the related shaft 17, being clamped against said base disk and against one another by means of a suitable nut 21 threaded upon the end of the shaft 17.

The upper and lower heads are, of course, disposed above and below a sheet A supported upon the table 15, which, of course, necessitates the provision of a suitable opening 22 in said table 15 through which the operative portions of the cutting and holding disks of the lower heads may extend into operative engagement with the sheet A.

Any suitable means may be provided to insure proper presentation of the forward end of a sheet A to be cut to the cutting and holding units 55 and to thereafter assist in guiding the sheet as it is advanced manually or otherwise through the machine. For example, there may be a suitable guide element 23 carried by the table 15 against which one side edge of the sheet A may 60 be disposed to insure alinement of any given row of the bonds 11 with the cutting points of any given pair of the cutting disks 18, 18.

Also, any suitable means may be provided for rotatably driving the shafts 17 and the cutting and holding disks carried thereby. In this connection and as illustrated by way of example in the present instance, the upper and lower shafts 17 may be provided at their upper and lower ends, respectively, with bevel gears 24 meshing 70 with companion bevel gears 25 on upper and lower suitably driven shafts 26 and 27 journaled in suitable bearings carried by the frame side elements 12, 12. The shaft 27 is driven from any source of power and has a sprocket thereon over 75

which a sprocket chain is trained to drive a sprocket on a stud shaft upon which is also a gear in mesh with a gear on shaft 26 as shown at the left of Fig. 1.

5 The cutting heads of each unit may, of course, be adjustable along the cross members 13 and 14 transversely of the machine to enable any given sheet A to be cut into strips of any desired widths.

In the operation of the machine a sheet A to be cut is placed flatly upon the table 15 with the rows of bonds 11 to be cut alined with the effective cutting portions of the cutting disks 18, the guide element 23 serving in this connection to facilitate a proper initial presentation of the forward edge of the sheet to the cutting and holding units. The sheet then is advanced manually, or otherwise, over the table 15 toward the cutting and holding units, and as the successive bonds of a row are presented to the cutting disks the bonds and strands to either side of said row are engaged above and below by the holding and guiding disks 19 whereby the sheet is held positively in position to insure that the bonds will be cut midway between their side edges so that ragged or barbed edges at the sides of the strips cut from the sheet will be avoided.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

35 We claim:

1. A machine for cutting expanded metal lath of the type having diamond-shaped openings defined by diagonal strands united with each other at the corners of the openings by bonds and wherein the strands and bonds are cross-sectionally inclined to the plane of the sheet and are disposed in stair-step relationship to each other, said machine having a support for a sheet of the lath to be cut, rotary shears comprising cooperating bond cutting disks disposed in planes at substantially right angles to the planes of the bonds of a sheet of lath disposed upon said support, said cutting disks being disposed at elevations to cut a row of bonds of the sheet midway between the side edges of the bonds when the sheet is advanced over said support toward said cutting disks, and in combination therewith the improvement which consists of sheet holding disks axially alined with said cutting disks and rotatable therewith and cooperating with each other to provide stepped marginal portions conforming to and fitting into the step-like spaces defined by the strands and bonds to either side of the row of bonds being cut, whereby the sheet is held in proper relationship to the cutting disks to insure cutting of the bonds midway between their side edges by said cutting disks.

2. A machine for cutting expanded metal lath of the type having diamond-shaped openings defined by diagonal strands united with each other at the corners of the openings by bonds and wherein the strands and bonds are cross-sectionally inclined to the plane of the sheet and are disposed in stair-step relationship to each other, said machine having a support for a sheet of the lath to be cut, rotary shears comprising cooperating bond cutting disks disposed in planes at substantially right angles to the planes of the bonds of a sheet of lath disposed upon said support, said

cutting disks being disposed at elevations to cut a row of bonds of the sheet midway between the side edges of the bonds when the sheet is advanced over said support toward said cutting disks, and in combination therewith the improvement which consists of stepped means rotatable with said cutting disks for cooperation with the step-like formations of the sheet to either side of the row of bonds to be cut to hold the sheet in a relationship to said cutting disks to insure cutting of the bonds midway between their side edges by said cutting disks.

3. A machine for cutting expanded metal lath of the type having diamond-shaped openings defined by diagonal strands united with each other at the corners of the openings by bonds and wherein the strands and bonds are cross-sectionally inclined to the plane of the sheet and are disposed in stair-step relationship to each other, said machine having a support for a sheet of the lath to be cut, rotary shears comprising cooperating bond cutting disks disposed in planes at substantially right angles to the planes of the bonds of a sheet of lath disposed upon said support, said cutting disks being disposed at elevations such that one is disposed above and the other below a sheet resting upon said support, said cutting disks further being disposed at elevations to cut a row of bonds of the sheet midway between the side edges of the bonds when the sheet is advanced over said support toward said cutting disks, and in combination therewith the improvement which consists of sheet holding disks above and below each cutting disk rotatable therewith and having their marginal portions disposed in stepped relationship to each other for cooperation with the step-like formations of the sheet to either side of the row of bonds to be cut to hold the sheet in a relationship to said cutting disks to insure cutting of the bonds midway between their side edges by said cutting disks.

4. A machine for cutting expanded metal lath of the type having diamond-shaped openings defined by diagonal strands united with each other at the corners of the openings by bonds and wherein the strands and bonds are cross-sectionally inclined to the plane of the sheet and are disposed in stair-step relationship to each other, said machine having a support for a sheet of the lath to be cut, rotary shears comprising cooperating bond cutting disks disposed in planes at substantially right angles to the planes of the bonds of a sheet of lath disposed upon said support, said cutting disks being disposed at elevations such that one is disposed above and the other below a sheet resting upon said support, said cutting disks further being disposed at elevations to cut a row of bonds of the sheet midway between the side edges of the bonds when the sheet is advanced over said support toward said cutting disks, and in combination therewith the improvement which consists of a plurality of sheet holding disks at least at one side of each cutting disk having their marginal portions disposed in stepped relationship corresponding to the stepped relationship of the strands and bonds of the sheet to either side of the row of bonds to be cut for cooperation with the said stepped strands and bonds of the sheet to either side of the row of bonds to be cut to hold the sheet in a relationship to said cutting disks to insure cutting of the bonds midway between their side edges by said cutting disks.

5. A machine for cutting expanded metal lath of the type having diamond-shaped openings defined by diagonal strands united with each other
